UNITED STATES PATENT OFFICE.

IDA K. MARTIN, OF MINNEAPOLIS, MINNESOTA.

DESIGN FOR A FLAG STAND.

Application filed January 16, 1928. Serial No. 24,894. Term of patent 14 years.

To all whom it may concern:

Be it known that I, Ida K. Martin, a citizen of the United States, residing at Minneapolis, in the county of Hennepin and State of Minnesota, have invented a new, original, and ornamental Design for Flag Stands, of which the following is a specification, reference being had to the accompanying drawing, forming part thereof.

I claim:

The ornamental design for a flag stand, as shown.

In witness whereof, I have hereunto set my hand this 12 day of January 1928.

IDA K. MARTIN.
